Inventor

Gustav A. Friess
By Rudolph G. D. Atty:

UNITED STATES PATENT OFFICE.

GUSTAV A. FRIESS, OF CHICAGO, ILLINOIS.

SHEET-DELIVERY MECHANISM FOR PRINTING-PRESSES.

1,252,681.

Specification of Letters Patent.

Patented Jan. 8, 1918.

Application filed November 23, 1916. Serial No. 133,047.

To all whom it may concern:

Be it known that I, GUSTAV A. FRIESS, subject of the Emperor of Germany, residing at Chicago, in the county of Cook and 5 State of Illinois, have invented certain new and useful Improvements in Sheet-Delivery Mechanism for Printing-Presses; and I do hereby declare the following to be a full, clear, and exact description of the invention, 10 such as will enable others skilled in the art to which it appertains to make and use the same.

This invention relates to improvements in printing presses, and more particularly to 15 improvements in sheet-delivery mechanism for printing presses.

The invention has for its main object to provide sheet-delivery mechanism for printing presses which will deposit sheets successively upon a support therefor in such a manner as to cause one edge of the sheet to first contact with the stack to be followed gradually by the entire surface of the sheet, thereby avoiding the formation of air 25 cushions between the sheets whereby the latter may become displaced and form an irregular stack.

The present invention relates more particularly to specific improvements in and 30 about the construction illustrated and described in my copending application for Letters Patent Ser. No. 88822 filed April 4, 1916. The general objects of the present invention are the same as those of the invention disclosed in said copending application, and the specific objects of the present invention relate more particularly to the 35 specific details of construction differentiating it from the aforesaid earlier invention whereby certain new and useful results are obtained, and will be easily understood from the following specification.

The invention consists in the features of construction and combinations of parts hereinafter fully described and claimed.

In the accompanying drawings illustrating a suitable embodiment of the invention:

Figure 1— is a top plan view partly in section of a printing press equipped with sheet delivery mechanism constructed in accordance with my invention.

Fig. 2— is a vertical longitudinal section of the same on the line 2—2 of Fig. 1—.

Fig. 3— is a fragmentary detail longitudinal section of the same on the line 3—3 of Fig. 1—.

Fig. 4— is a fragmentary vertical transverse section of the same on the line 4—4 of Fig. 7—.

Fig. 5— is a fragmentary detail vertical longitudinal section on the line 5—5 of Fig. 1—.

Fig. 6— is a fragmentary detail top plan view showing certain details of adjusting mechanism employed.

Fig. 7— is a fragmentary detail horizontal section on the line 7—7 of Fig. 4—, certain parts being shown in elevation.

Fig. 8— is a fragmentary detail section on the line 8—8 of Fig. 9—.

Fig. 9— is a fragmentary detail section on the line 9—9 of Fig. 1—.

One of the principal objects of the present invention is to provide sheet-delivery mechanism for printing presses which includes means for so engaging the sheet as to place the same under light tension by means of a yielding engagement of the sheet whereby it is drawn from the printing elements and delivered upon a carrier therefor and maintained accurately positioned during travel and so deposited accurately upon the support for the stock of sheets.

In printing on thin sheets of paper there is a decided tendency of the printed sheets to curl as they leave the printing elements, and such curling or warping of the same interferes with their proper delivery besides resulting, frequently, in their becoming folded upon the stock.

Another object of this invention is, therefore, to provide sheet-delivery mechanism in which curling or warping of the printed sheets during travel is obviated.

Another object of the present invention is to provide sheet-carrying means associated with the sheet-engaging mechanism referred to in the preceding paragraph which will receive and carry the printed sheets face up and deliver the same upon a stack in the manner hereinbefore set forth.

In the accompanying drawings illustrating the preferred embodiment of the invention, 1 and 2 represent the printing and 105 tympan cylinders respectively, of a printing press, which are suitably driven to rotate in unison to print sheets passing there-

between. The cylinder 2 is usually provided with suitable sheet-gripping mechanism omitted from illustration, but which may be of the construction illustrated and described in my copending applications for Letters Patent Ser. Nos. 88,822 and 77,839, respectively, and particularly adapted to the needs of the present construction. The sheets after being printed are stripped or raised from the cylinder 1, by means of the aforesaid gripping mechanism, and pass upon a plate 2^a which is equipped with stripper fingers 2^b which approach, but do not contact with, the surface of the cylinder 2. From the plate 2^a the sheets are delivered successively upon a carrier 3 consisting of a plurality of tapes or narrow belts trained over pulleys carried by shafts 4 and 5 respectively, the latter of which is driven by means of a suitable gear including the spur-pinion 6. The shaft 4 is journaled in bearings in the side-plates 7 mounted upon portions of the frame of the machine, and between which the several belts 3 are disposed; said plates 7 being disposed contiguous to the ends of the cylinder 1.

There are also journaled in bearings in said plates 7, two shafts 8 and 9 respectively, carrying pulleys 10 and 11 over which a series of belts 12, similar to the belts 3, are trained. The latter travel in the opposite direction from the belts 3, and at the same speed so that sheets supported upon the belts 3 will have their printed faces opposed to the belts 12, which will coact to a certain extent with the belts 3 to effect delivery of said sheets and prevent movement thereof relatively to the belts 3 during such delivery. The principal function of the belts 12 is, however, to prevent warping or curling of the sheets by holding down the rising portion or portions of the sheets carried by the belts 3. This tendency of the sheets to curl or warp is only momentary after leaving the printing elements so that it is unnecessary to extend the belts 12 over a greater length of travel of the sheets than shown in the drawings. The pulleys 10 and 11 over which the said belts 12 are trained are keyed to the shafts 8 and 9 respectively, being non-rotatable relatively to the latter, but longitudinally adjustable on the same, the direction of their adjustment being parallel with the axes of the cylinders 1 and 2. Extending parallel with said shafts 8 and 9 are screw-shafts 13 and 17, each of which is journaled at one end in a bearing in one of the side plates 7, and at its other end in a bearing 14^a carried by the cross-rod 15 mounted in its ends in said plates 7. Each of the shafts 13 and 14 is substantially one-half the length of the shafts 8 and 9 respectively, there being shafts 16 and 17, similar to the shafts 13 and 14, axially aligned therewith and extending from the other side of

the bearing 14^a to the other of said plates 7, and being oppositely threaded from said shafts 13 and 14.

Each of the pulleys 10 and 11 is provided with an annularly grooved hub 18 and 18^a in which the bifurcated arms 19 of threaded sleeves 20 engage, the latter having threaded engagement with the screw-shafts 13, 14, 16 and 17 respectively. Each of the shafts 13 and 14 and their companion shafts 17 and 16 carries a bevel pinion 21 meshing with the bevel gears 22 on transverse manually operable shafts 23 journaled in bearings in brackets on the plates 7, by means of which the pair of shafts 13 and 14, and the pair of shafts 16 and 17 respectively, are simultaneously rotated to effect an adjustment of the pulleys 10 and 11 toward or from the bearings 14^a. The pulleys disposed at one side of said bearings may be adjusted independently of those at the opposite side of said bearings, thus enabling said belts to be relatively adjusted to effect delivery of sheets from the end-portions of the cylinders 1 and 2 in the event that said sheets are printed at one side of the middle portion thereof; this being frequently resorted to for purposes of economy, as will be readily understood.

The hubs 18 of the pulleys 10 are of greater length than the hubs 18^a of the pulleys 11. The former constitute sleeves mounted on the bushings 24 carrying the pulleys 10 and constituting the hubs of spur-pinnions 25. The hub-members or sleeves 18 are rotatable on the bushings 24, and are provided with arms 26 carrying stud-shafts 27 on which idle-pinions 28 are rotatably mounted. The latter mesh with the spur-gears 25 and also with spur-gears 29 on the stud-shafts 30 carried in the outer ends of said arms 26. Rigid with the spur-gears 29 are rollers 31 having face or tread portions 32 of rubber or similar elastic material. The said rollers 31 are adapted to be so adjusted in position relatively to the surface of the plate 2^a as to not contact therewith, but spaced therefrom a distance less than the thickness of the sheets so that each of the latter will be engaged thereby and moved over the surface of said plate and upon the belts 3. Said tread portions 32 of the rollers 31 are rotated at a surface speed which is coincident with the surface speed of the roller 2, and preferably slightly in excess of the latter. Said tread portions are held firmly in position relatively to the surface of the plate 2^a by means of helical compression springs 33 each disposed between an arm 34 carried by the member or sleeve 18, and an arm 35 rigid with the sleeve 20 on the shaft 13. The latter is provided with a threaded opening in which the threaded shank 36 of a hand-wheel 37 engages; said shank being also engaged with the arm 34.

so as to be freely rotatable relatively to the latter and to permit a limited relative pivotal motion between said parts. The hand-wheel 37 limits the movement of the sleeve 5 or member 18 in one direction by means of the stop member or head 38 on said shank 36.

In printing on very thin sheets of paper considerable trouble is experienced in delivery thereof. Said sheets have a tendency 10 to adhere rather firmly to the surface of the carrier or tympan cylinder and when stripped from the latter, they tend to curl up and warp. As said sheets are relatively delicate and easily torn or injured, they 15 must be handled very carefully.

In order to facilitate stripping such sheets from the carrier cylinder I provide the latter with the sheet-gripping mechanism described and claimed in my copending applications for Letters Patent, Ser. Nos. 88,822 20 and 77,839. This includes a radially reciprocal anvil member 30^a (see Figs. —8— and —9—) upon which the forward edge of the sheet rests and is engaged by the 25 gripper fingers 30^b. The latter are spring-held but actuated by means of reciprocal rack-bars and pinions described and claimed in the last-named copending application. The said anvil member 30^a is provided with 30 recesses 30^c between the points of engagement of said gripper fingers therewith and into which the stripper finger 2^b projects to engage the under surface of the sheet as the latter is raised from the cylinder 35 surface by the outward movement of said anvil member 30^a. This movement also causes air entering below the edge of the sheet to assist in stripping the same from the cylinder, and this is further promoted by the 40 rollers 31 which keep the sheet moving steadily until they are disposed between the several belts of the delivery mechanism.

The shaft 8 is equipped with a sprocket 39 which is geared by means of a sprocket 45 chain 40 to the sprocket 41 on the counter-shaft 42 journaled in bearings in one of said frame-members 7, and in a portion of the frame of the machine opposite the same. The said shaft 42 also carries a sprocket 43 50 geared by means of a sprocket chain 44 and a sprocket 45 to the countershaft 46. The latter is geared by means of the sprocket 47, sprocket chain 48 and sprocket 49 to the drive-shaft 50.

The shaft 46 is also equipped with a sprocket 51 geared by means of sprocket chain 52 with the sprocket 53 on a shaft 54. The latter is equipped with a spur-gear 55 which meshes with the spur pinion 6 on the shaft 5, and with a spur pinion 56 on a shaft 57. Both shafts 5 and 57 are journaled at their ends in bearings in the side-members 58 of the frame of the machine.

Disposed to project beyond one end of the 60 press-frame proper is a table or support 59 for

the printed sheets. Disposed at opposite sides of the same are two guide-rods 60 which are secured at their inner ends to standards 61 on the machine-frame disposed to terminate below the shaft 57. Reciprocably movable 70 on said guide rods 60 are carriages 62. Journaled in bearings in the latter is a shaft 63 over which belts 64 are trained, the latter being also trained over pulleys 65 on the shaft 57. Extending parallel with and 75 contiguous to the latter are two idle shafts or rollers 66 and 67 respectively, as more particularly shown in Fig. —5—.

The carriages 62 are connected by means of the connecting rods 68 with carriages 69 80 rigid with rack-bars 70 which are slidable in guides 71 on the machine-frame at the other end of the latter. The said rack-bars 70 mesh with spur-pinions 72 carried by a shaft 73, and said pinions in turn mesh with 85 spur gears 74 on a shaft 75, all of said shafts being journaled in bearings in the frame members 58. The shaft 75 carries the spur-pinions 76 which mesh with the spur-gears 77 on a shaft 78. The latter carries spur pinions 79 meshing with the segmental gear 80 on a rock-shaft 81. Rigid with the segmental gear 80 is another segmental gear 82 of smaller radius which meshes with the reciprocal rack-bar 83 suitably mounted 90 to move reciprocally in guides on the frame of the machine. The said rack-bar 83 carries an anti-friction roller 84 which is engaged in the groove of a cam 85 mounted on the drive-shaft 50. The groove of said cam 100 is eccentric to the axis of the shaft 50 and is provided with an inwardly deflected portion 86 in which the roller 84 is shown to be engaged in Fig. —2—. During the engagement of the roller in this portion of the cam 105 the rack-bar 83 is maintained at rest for a very short interval, but during the balance of the rotation of the cam 85 through an arc of substantially three hundred and thirty degrees, more or less, reciprocal movement will be imparted to said rack-bar 83, and thereby to the rack-bar 70 and carriages 69 and 62 at intervals corresponding or synchronized with the intervals of delivery of 110 printed sheets from the cylinders 1 and 2. 115

Journaled in bearings in the carriage 69 is a shaft 87 carrying pulleys over which the belts 64 are trained, the latter being also trained over the said shafts 66 and 67, and over idle-pulleys 88 carried by a shaft 89 120 journaled in bearings in the rocking arms 90 having suitable pivotal support on the frame of the machine. The said arms 90 are engaged with the helical tension springs 91 which are also engaged with a cross-bar 125 92 suitably mounted in the frame of the machine whereby said pulleys 88 will serve to maintain the belts 64 taut.

It will be obvious from the foregoing description that as the carriages 69 and 62 are 130

reciprocated in unison by virtue of their connection with each other, the pulleys 62 and 87 will also reciprocate, thereby causing the belts 64 to travel longitudinally independently of their travel due to their being driven from the shafts 57. The surface speed of the pulleys 65 on the shaft 57 is preferably exactly equal to the speed of reciprocal movement of the carriage 62, so that sheets received from the belts 3 will continue to move at the same speed due to their engagement with the belt 64 and during the movement of the carriages 62 in the same direction; whereas, as soon as the said carriages 62 begin their reverse movement the belts 64 by reason of their travel continuously in the same direction will effect a deposit of the sheets front-edge first upon the table or support 59, the belts 64 being thus withdrawn from beneath the sheets while the latter remain at rest so far as further longitudinal movement is concerned.

It will be noted that the belts 12 are so disposed relatively to the belts 3 that the portions of the former opposing the carrier portions of the latter are spaced from the same, said space tapering or contracting toward the delivery point of the belts 3. The taper of this space may be adjusted by means of the belt tighteners associated with the belts 12. Each of the latter consists of a threaded member 93 engaged in a sleeve 94 integral with a sleeve 20 and extending transversely thereto. The threaded member 93 carries an anti-friction roller 95 adapted to bear upon and deflect the belt 12 with which it is associated to force the portion opposing the receiving part of the belts 3 toward the latter, as shown in Fig. 3.

The belts 12 may thus be adjusted to engage the printed surfaces of the sheets though their purpose is mainly to aid in holding the sheets against displacement on the belts 3 by air currents or other disturbing influences.

The rollers 31 and belts 3 and 12 have a uniform speed which is somewhat greater than that of the surfaces of the printing elements or speed of delivery of sheets from the latter, and the relatively light frictional engagement of the latter by said rollers and belts thus serves to merely pull the sheets straight without having any tendency to pull the sheets from between the printing elements.

The operation of the invention will be readily understood from the foregoing specification.

While I have illustrated the preferred embodiment of the invention in the accompanying drawings, it will be understood that the construction shown and described may be changed and varied in details without departing from the invention as defined in the appended claims.

I claim as my invention:

1. In a printing press, the combination with the printing elements and sheet-carrying means, of a surface interposed between the same, and sheet-engaging mechanism 70 coacting with said surface for engaging sheets delivered from said printing elements and deliver same to said carrying means.

2. In a printing press, the combination with the printing elements and sheet-carrying means associated therewith, of a stripper-plate interposed between said parts over which sheets are adapted to travel successively, and a pair of driven rollers coacting with said plate for engaging sheets passing 80 over the same and move them onto said carrier.

3. In a printing press, the combination with the printing elements and sheet-carrying means associated therewith, of a stripper- 85 plate interposed between said parts over which sheets are adapted to travel successively, and a pair of driven rollers coacting with and disposed above said plate for engaging the upper surfaces of sheets passing 90 over the same and move them onto said carrier.

4. In a printing press, the combination with the printing elements and sheet-carrying means associated therewith, of a stripper- 95 plate interposed between said parts over which sheets are adapted to travel successively, and a pair of friction surfaced driven rollers associated with and disposed above said plate for engaging the upper surfaces 100 of sheets passing over the same and move them onto said carrier.

5. In a printing press, the combination with the printing elements and sheet-carrying means associated therewith, of a stripper- 105 plate interposed between said parts over which sheets are adapted to travel successively, and a pair of friction surfaced driven rollers disposed contiguous to and out of surface contact with the sheet-carrying surface of said plate and adapted to engage the upper surfaces of sheets for moving them over said plate and onto said carrying means.

6. In a printing press, the combination with the printing elements and sheet-carrying means associated therewith, of a stripper- 115 plate interposed between said parts over which sheets are adapted to travel successively, and a pair of friction surfaced rollers associated with and disposed above said plate for engaging the upper surfaces of sheets passing over the same and move them onto said carrier and gearing between said rollers and the drive gear of the press for rotating said rollers at a surface speed not 120 less than the surface speed of the printing elements.

7. In a printing press, the combination with the printing elements and sheet-carrying means associated therewith, of a stripper- 130

- plate interposed between said parts over which sheets are adapted to travel successively, driven sheet-engaging elements associated with said plate for engaging sheets 5
5 passing over the same and move them onto said carrier, means supporting said sheet-engaging elements, and means for adjusting the position thereof with respect to said plate, said means including a spring for normally forcing the same toward said plate. 10
8. In a printing press, the combination with the printing elements and sheet-carrying means associated therewith, of a strip-
15 per-plate interposed between said parts over which sheets are adapted to travel successively, driven sheet-engaging elements associated with said plate for engaging sheets passing over the same and move them onto said carrier, means supporting said sheet-
20 engaging elements, a spring normally forcing the latter toward said plate, and adjustable stops for limiting the movement thereof in said direction. 25
9. In a printing press, the combination with the printing elements, of a sheet carrier inclined downwardly away from the printing elements adapted to receive the printed sheets successively, means associated with said carrier for preventing curling or warp-
30 ing of the printed sheets on the carrier during travel, and means for maintaining said carrier continuously in motion at a speed exceeding the speed of delivery of sheets from said printing elements. 35
10. In a printing press, the combination with the printing elements, of a sheet carrier inclined downwardly away from the printing elements adapted to receive the printed sheets successively, means associated with said carrier for preventing curling or
40 warping of the printed sheets during travel,
- and means for maintaining said carrier, and said means associated therewith continuously in motion at a speed exceeding the speed of delivery of sheets from said print- 45
ing elements. 50
11. In a printing press, the combination with the printing elements and sheet-carrying means associated therewith, of a strip-
55 per-plate interposed between said parts over which sheets are adapted to travel successively, and a pair of friction surfaced rollers associated with and disposed above said plate for engaging the upper surfaces of sheets passing over the same and move them onto said carrier and gearing between said rollers and the drive gear of the press for rotating said rollers at a surface speed exceeding the surface speed of the printing elements. 60
12. In a printing press, the combination with the printing elements, sheet-carrying means adapted to receive sheets therefrom, and means for effecting continuous travel of said carrier at a speed exceeding the speed 65
of delivery of sheets from said printing elements, of rotatable elements disposed between said printing elements and said carrier for frictionally engaging sheets to cause the passage thereof from said printing elements, upon said carrier, and gearing between the latter and said rotatable elements for causing the latter to rotate at the same speed of surface travel as said carrier. 70
- In testimony whereof I have signed my name in presence of two subscribing witnesses. 75
